UNITED STATES PATENT OFFICE.

JOHN E. BOLLING, OF CHICAGO, ILLINOIS, ASSIGNOR TO DRYING SYSTEMS, INC., OF CHICAGO, ILLINOIS, A CORPORATION OF ILLINOIS.

ATMOSPHERICALLY-CONTROLLED SWITCH.

Application filed January 11, 1928. Serial No. 80,548.

This invention relates to improvements in control instruments such as thermostats and the like, and more particularly to the electrical switch mechanism therefor, and is chiefly characterized by providing a counterweight for the shifting mercury globule.

Heretofore difficulty has been encountered in such instruments in obtaining a high degree of accuracy at the point at which the electrical switch is operated, on account of the resistance suddenly added to the movable element of the device in overcoming the unbalanced weight of the mercury globule. It is, therefore, an object of this invention to improve the operation of the instrument by providing means for suitably balancing the globule in the various positions.

An illustrative embodiment of the invention is shown in the accompanying drawings, in which:

Figure 1 is an elevation of the switch and adjacent portions of an atmospheric control instrument.

Fig. 2 is a view similar to Fig. 1, showing the switch in the opposite position.

Fig. 3 is a diagram of the movement of the responsive element of the instrument.

Fig. 4 is a section substantially on the line 4-4 of Fig. 1.

In the drawings, the glass switch bulb 1 is provided with contacts 2 and 3 at the outer end thereof. In the position shown in Fig. 1, the switch bulb is tilted to the left so that the mercury globule 4 has run over to the outer end, and serves as a contactor between the switch points 2 and 3. The bulb is held in the clip portion 5 of the sheet metal saddle 6, by means of the bolt 7. A lug 8 is stamped out and bent downward from the bottom of the member 6 to provide a contact point for resting on the end of the movable member 9 of the instrument. At the inner end of the sheet metal member 6, the flat portion 10 is bent downwardly and terminates in a threaded portion 11 for the counterweight 12. The pivotal mounting of the switch comprises a post 14 secured in the frame 15 of the instrument, and the post 14 engages in the lugs 16, which are bent up from the flat tail portion 10.

As shown, the switch bulb 1 is mounted above the pivot 14. The switch overhangs to the left of the pivot, and the counterbalance is hung below the pivot so that the horizontal movement of the counter-balance is

opposite to the horizontal movement of the bulb portion of the switch, and changes oppositely to the shifting movement of the mercury globule 4 as the switch is rotated.

In this arrangement the weight of the switch bulb and the clip 6 serves to hold the contact point 8 resting on the end of the member 9, and the counter-balance 12 is to be proportioned for counter-balancing only the globule 4. When the element 9 raises in shifting the switch from the position shown in Fig. 1 to the position shown in Fig. 2, the mercury will cling somewhat to the switch points and then run to the opposite end of the bulb when the bulb angle is a few degrees above the horizontal. During the tilting movement the counter-weight 12 is moving under the pivot 14, and in the off position, Fig. 2, the counter-balance 12 may even be slightly to the left of the pivot 14 when the globule is to the right of the pivot as shown in Fig. 2. It is to be understood that the member 9 is moved in any well-known manner, such as by a thermal expansible bellows, a Bourdon tube, or other well-known responsive element.

It being understood that the member 9 is moved a short distance up or down by changes in temperature, it is apparent that the weight of the glass bulb and the holder 6 on the actuating rod 9 is substantially constant since the vertical line through the center of gravity of these parts does not shift materially with respect to the axis. But the mercury globule 4 shifts from a position to the left of the axis to a position slightly to the right, Fig. 1 and Fig. 2. This of course produces a variable load on the actuating rod 9 which is found to be sufficient to materially affect the accuracy of the instrument.

The counterbalance 12 is provided solely for the purpose of compensating for the weight of the mercury 4. By suspending the counterweight below the axis 14, the counterweight moves oppositely to the mercury. In the position shown in Fig. 1, the mercury exerts a counterclockwise rotational movement about the axis 14, which is compensated for by the clockwise rotational movement exerted by the counterweight 12.

In the "off" position shown in Fig. 2, the mercury is over or slightly to the right of the axis while the center of gravity of the counterweight is below or may be slightly to the left of the axis. In this manner the

difference in the load, or the resistance applied to operating member 9 by the changes in the position of the mercury globule is overcome in a simple manner.

5 For illustrating the effect of the weight of the mercury globule, in Fig. 3, the distances on the X axis, represent roughly the different temperatures, and the lengths on the Y axis, for the curve *b*, represent the various 10 positions of the movable member 9. The heights on the Y axis for the resistance curve *d* represent the resistances opposing the movement of member 9. The curve *d* illustrates the approximate relative resistances 15 corresponding to the various temperatures resulting in the movement curve *b*, assuming that the increase in energy for moving is substantially constant for equal changes in temperature. In instruments commonly 20 used, the resistance is usually a spring, and accordingly increases at an even rate, as represented by the general slope of the line *d*, and the slope of the movement curve *b* would, of course, correspond to the slope 25 of the curve *d* with even rates of increase in the power. Line *f* represents the point at which it is desired to have the instrument operate, which would be a predetermined 30 temperature providing the instrument is a thermostat. Without means for counter-balancing the mercury globule the resistance would start to increase at temperature *h* where the movable element starts to lift the end of the switch bulb. The resistance 35 would increase to the high point *k* where the mercury globule is freed and starts to run to the opposite end of the bulb. Therefore at the precise position where accuracy is 40 desired, the movement is slowed up, as shown by the curve *e*, and the actual point of breaking the electrical switch will be around the temperature *m*, which is, as a result, a variable distance from the temperature *f*. Accordingly, in this invention, 45 by providing means to counter-balance the weight of the mercury, the resistance to movement will not be suddenly increased, and the resulting action of the switch will be much more accurate.

Although but one specific embodiment has 50 been herein shown and described, it will be understood that numerous details of the construction shown may be altered or omitted without departing from the spirit of this invention.

55

I claim:

1. In combination, in an atmospherically controlled device having a movably responsive member, a pivotally mounted mercury bulb switch resting on said member and having the mercury globule thereof shiftable with respect to the pivotal axis, and a counterweight attached to the switch and movable therewith for counterbalancing the weight of said globule in the extreme positions.

2. In combination, in an atmospherically controlled device having a movably responsive member, a bulb switch resting on said member, said switch having a pivot and having a mercury contactor globule shiftable with respect to said pivot and an adjustable counterweight for counter-balancing said globule said counterweight attached to said switch and positioned on the opposite side of the axis.

3. In combination, in an atmospherically controlled device, a switch bulb tiltable by said device and having a pivot and a mercury contactor globule which is shifted in horizontal relation towards and away from said pivot by tilting the bulb, and a counterweight attached to said bulb and positioned below said pivot to counter-balance said globule.

4. In combination, a switch comprising a glass bulb having a shiftable mercury globule contactor, said bulb mounted on a fixed axis for tilting to either side of the horizontal position to shift said globule, and a counterweight attached to said bulb and positioned on the opposite side of the axis to produce counter-rotational movements to the rotational movements produced by the globule in either extreme position.

Signed at Chicago this 6th day of January, 1926.

JOHN E. BOLLING.
